UNITED STATES PATENT OFFICE.

MITCHELL CARTER, OF SALT LAKE CITY, UTAH, ASSIGNOR TO THERMIC GENERATING COMPANY, A CORPORATION OF UTAH.

OIL BURNER.

Application filed September 10, 1924. Serial No. 736,939.

To all whom it may concern:

Be it known that I, MITCHELL CARTER, a citizen of the United States, residing at Salt Lake City, in the county of Salt Lake and 5 State of Utah, have invented certain new and useful Improvements in Oil Burners, of which the following is a specification.

My invention relates to oil burners, and has for its object to provide a new oil burner 10 wherein oil is converted into a vapor or gas which is used as a fuel for heating purposes, and in my burner the exits of the gas are so constructed that they will not so readily hold carbon in or around the exit ports, and 15 the generator is so constructed that greater heat may be supplied to vaporize the oil as it passes through the generator, and particles of carbon which usually accumulate in the generator are destroyed or burned. 20 A further object is to provide an apparatus which will vaporize the oil in a generator having an open exit commensurate with the heat desired and thereby eliminate the noise of burners which atomize the oil instead of vaporizing it, and also to provide a slow, steady flow of gas through the jets. 25 A further object is to provide a flame by the burning gas striking against a concave surface whereby the flame is supplied with 30 oxygen from only one side thereof until said flame has passed the generator, also to control the shape of the flame and thereby increase the amount of available oxygen and maximum combustion. These objects I accomplish with the device illustrated in the 35 accompanying drawings in which similar letters and numerals of reference indicate like parts throughout the several views, and as described in the specification forming a part 40 of this application and pointed out in the appended claims.

In the drawings in which I have shown the best and most substantial embodiment of my invention, Figure 1 is a diagrammatic plan showing the substantial features of my device, parts cut away to show how the device is used in the ordinary house furnace or heating plant. Figure 2 is plan view of the device, with the generator cut away. Figure 3 is a side elevation of the device. Figure 4 is a vertical section of the device on line 4-4 of Figure 2. Figure 5 is an end elevation of the gas distributing tubes or burners. Figure 6 is a longitudinal section 55 of the casing for the valve shown in Figure

8. Figure 7 is a longitudinal section of the casing for the valve L. Figure 8 is a plan view of the regulating valve and stem. Figure 9 is a vertical section of the triangular member 30. Figure 10 is a longitudinal section cutting the two valves L and P, and their respective casings, on line 10-10 on Figure 9.

My invention consists of a priming pan A having radially disposed braces 1 which are 60 integral with a base support and said pan A and lead therefrom, to an annular base-support B. An asbestos mat J is provided in said receptacle A for use as a lighter, as hereafter explained and described. An oil 65 supply pipe 9 connects the oil tank O with the valve controlled conduit 10, and the flow of oil is by gravity, with the tank O about four feet higher than the conduit 10 or slight pressure may be used. A needle valve 70 C controls and regulates the flow of the oil from the tank to said conduit 10, which is used first for priming, by allowing, when the device is operated, ten to twelve drops 75 of oil to flow into receptacles A. The generator D is mounted above and concentric with the said receptacle A by the tubes 12 and 13; the said tube 12 opens at its lower end into the said conduit 10, and at its upper end into the said generator D, and the tube 13 is 80 similarly connected at its upper end with the interior of said generator D. The said tube 13 is curved and bent downwardly and then laterally in a diametrical direction as to 85 said receptacle A and is welded on the valve 90 nozzle 14. The said tube 13 is fastened on the upper edge of said receptacle B by clamp 15. The said generator D consists of a hollow circular saucer-shaped or concavo-convex member 16 with the concave side outward and with the convex side reinforced to 95 give greater strength. On the outer edge of said saucer-shaped member 16, another concavo-convex plate 18 is welded which forms the top of said generator D, with its 100 convex side outward. A reinforcement member is secured between the member 16 and the plate 18. The joint between the perimeter of said plate 18 and outer edge portion of said saucer-shaped member 16 is 105 welded to make a tight joint and one that will withstand contraction and expansion of said members, and also the expansive action of the vapors generated within said generator, at a temperature up to 1600 de- 110

5   degrees F. which temperature may at some time be required in using the device. The concavo-convex form given the top and bottom of said generator gives the greatest strength to withstand the pressure of the gas or vapors generated in the device and the expansion and contraction of the metal.

10   The said valve nozzle 14 is tubular in form and is welded on the tube 13. The other end portion of said valve nozzle 14 is tapered and given a conical shape with a closed end. An exit port 19 is cut through the tapered wall of said nozzle 14 through which the gas flows. A tubular valve case 20 is carried on said nozzle 14, and one portion of the interior of said case 20 is frusto-conical in form to closely fit the exterior of said valve nozzle 14, and in the wall of said case are bored a plurality of 15 ports, each of which may be brought into alignment with said exit port 19 by rotating or partially rotating said case 20. A plurality of jets 21, each of which is given the form of a tube, are detachably secured 20 in the wall of said valve case 20 and conforming respectively on their exterior with the ports in the wall of said valve case 20. The said jets 21 extend radially in the form of hollow spokes from the said 25 valve case 20. The exits from the said jets 21 are of different sizes, and their lengths are graduated in order that the longest burner will have the smallest exit and the shortest burner will have the largest 30 exit. One of said ports in the wall of said case 20 may not have a jet as the exit port 19 in the nozzle 14, may have the same size as the largest port in the wall of said valve case 20.

35   An operating rod 22 is pivoted in the end of said valve case 20 by the pin 23, which rod 22 is mounted for rotation in the bearing 24. A regulator dial 25 is secured on the end of said rod 22 by which said rod 40 may be partially rotated in either direction, and on said dial is a graduated index 45 consisting of the numerals 1 to 6 inclusive, clock-wise and concentrically disposed, as to said wheel. The said numerals are spaced 50 apart to indicate to the operator that when the smallest of said burners 21 is pointed vertically the index numeral 1 will show at the top of said regulator dial 25, and the regulator dial 25 is notched on the perimeter 55 to receive the end of the jet indicator 26, which is a spring that is secured on the valve case 35.

60   A thermostat K is provided consisting of a brass rod or pipe 2 threaded externally at one end to secure it to the base B. At the other end it enters the thermostat valve L, through the packing nut 26. The said thermostat valve L consists of a cylindrically shaped casing 29, which is externally 65 threaded at each end as at 3 and 4, and

centrally bored with three different sized holes as at 5, 6, and 7 to form a seat for the conical end portion of the valve L. The said packing nut 26 is screwed on the threads 3 and closes that end of the valve. 70 A cap nut 8 is screwed on the threads 4 of the said casing 29 which nut carries a spiral spring M, that bears at its other end on said valve L. Integral with said casing 29 is a triangular member 30 which forms the 75 support for the oil supply pipe 10, and the housing or case for the regulating valve P, and is also longitudinally bored to form the conduits 31, 32, and 33. The main oil supply pipe 10 is screwed into the base of 80 said triangular member 30 and has ports in said pipe in alignment with said ports 31, 32, and 33, and another port is provided as shown at 34 in the base of said triangular member, which port is larger than either of 85 the ports 31, 32, or 33, and connects with the valve C, which valve regulates the priming oil. At the apex of said triangular member 30 is provided a cylindrical casing 90 35 which is externally threaded at each end. On one end is screwed a packing nut 36, through which the valve stem 40 is carried, and on the other end of said casing 35 is screwed the adjusting nut T. The said nut T is internally threaded at one end portion with left hand threads to receive the end of the casing 35, and is internally threaded at the other end with right hand threads to be secured on a portion of the 95 valve stem 40, which end is also externally threaded to receive a packing nut 38. The said casing 35 is centrally bored with two sized holes which are tapered toward each other to form a frusto-conical valve seat, and in which is operated the said regulating valve P. The said valve P is a portion 100 of the said valve stem 40, which stem is externally threaded at both ends, on one end of which is secured the regulator dial 25, and on the other end of said stem is 105 screwed the spring housing 41, one end portion of which is internally threaded to receive a regulating plug 42, and the end of the valve stem 40, the other end portion carries a spiral spring 43, and the end of 110 the operating rod 22, with the said spring 43 bearing against the said rod 22 and the regulating plug 42. A portion of said valve stem 40 contiguous the said valve portion P is externally threaded with right hand threads, as shown at 44 to receive the said 115 adjusting nut T.

120   The operation of my device is as follows:

125   From ten to twelve drops of oil are allowed to flow from the main oil supply pipe 10 through the valve C and the port 34 into the priming receptacle A. Said valve is then closed and the oil in the receptacle A is ignited. The heat from the burning oil will vaporize the oil remaining in the pipe 13 130

and valve nozzle 14 forming a gas. As the heat increases the gas expands and flows out of either of the jets 21 which is in alignment with port 19 and is ignited by the flame of the priming oil. The flames from the remaining priming oil and the flowing gas will in about three minutes vaporize all of the film of oil in the generator D and in pipes 12 and 13 and the heat will be sufficient to operate the thermostat K and through said thermostat open the valve L and allow a full flow of oil to flow through the regulating valve P. And thereafter the operation is continuous and may be manually regulated by turning the regulator dial and its connections, the valve P, the rod 22, casing 20 with jets 21 to bring the desired jet 21 into alignment with port 19 in the sleeve valve 20, which regulates the oil for the particular jet and flow desired.

If at any time it is desired to increase or diminish the heat the operator manually turns the regulator dial 25 to bring the desired jet to the vertical position and the heat will be diminished or increased as required.

Should the flame become accidentally extinguished for any reason the thermostat will automatically cut off the supply of oil and the burner will be extinguished thereby eliminating the danger from flooding the oil into the base of the furnace.

I regulate the heat in three ways heretofore not known and practiced in oil burners, viz: first, the supply of oil, second, the size of the case nozzles, third the spacing of the flame from the bottom of the generator.

The generator D is designed to present the maximum resistance to the flame, the bottom being concave so the expanding, burning gases from jets 21 will be presented to the bottom surface of the generator at about a right angle. All pipes, jets or ports of the generators and sleeve valve 20 are so constructed that they offer the minimum resistance and friction to the gases. The ports of the jets are so spaced from the bottom of the generator that the gas flowing therethrough gathers just enough oxygen from the surrounding air to start combustion under the bottom of the generator and not enough oxygen to make complete combustion. Additional oxygen is supplied from the air to the flame exposed to the air above the generator and this flame has a high temperature. The complete combustion takes place after the flame spreads out and after passing the generator. The flame is thin and sheet like and presents a maximum surface to the atmosphere taking on oxygen very readily to complete combustion. The flame is even and circular and has practically no ends and the heat is thrown out against the walls of the fire box within which the device is used. The burner is so regulated that

it operates with about one-half pound pressure in the generator thereby getting a better cracking of the oil into gas and eliminating the noise common with most oil burners and producing perfectly dry hydrocarbon gas. There is no danger of back fire from an air bubble or water bubble in the jet line causing the flame to become extinguished momentarily and igniting again, for after the oil is turned completely off it takes about three minutes for the flame to go out and the gas to cease flowing.

Having thus described my invention and its operation I desire to secure by Letters Patent and claim:—

1. An oil burner comprising an initial oil burning receptacle; a concavo-convex hollow generator spaced above said oil receptacle; an oil supply pipe connecting an oil supply with the interior of said generator; a U-shaped gas tube leading from the interior of said generator to a valve nozzle; a valve nozzle having a port in its side wall; a sleeve valve case rotatable on said valve nozzle and having a plurality of radially extended jets therein, of different lengths, and sized bore.

2. An oil burner comprising an oil supply pipe; a concavo-convex hollow generator connected with said pipe; means for the initial heating of said generator; a gas tube connected at one end with said generator; a frusto-conical valve nozzle on the other end of said tube and having a port in its side wall; a nozzle case having an opening in one end conforming with the shape of said valve nozzle and having a plurality of ports in its side wall, adapted to be brought into alignment with the port in said valve nozzle; centrally bored radially disposed jets in each of the ports in said case and of different lengths; and means to rotate said nozzle case.

3. An oil burner comprising a hollow circular generator having spaced apart concavo-convex top and bottom with the concave side of both turned in the same direction and toward the flame jets; means to supply oil to said generator; a curved gas pipe to allow gas to flow from said generator; a frusto-conical valve nozzle secured on the end of said gas pipe and having an exit port in its side wall; a rotatable casing conforming to the exterior surface of said valve nozzle; one or more flame jets therein of different lengths and sizes, each adapted to be brought into alignment with the port in said valve nozzle and to direct a flow of gas toward the under face of said generator; and means to regulate the flow of oil into said generator.

In testimony whereof I have affixed my signature.

MITCHELL CARTER.
